SUCTION CLEANER

Roy D. Livingston, North Canton, Ohio, assignor
to The Hoover Company, North Canton, Ohio,
a corporation of Ohio

Application April 3, 1942, Serial No. 437,518

5 Claims. (Cl. 230—114)

The present invention relates to suction cleaners and more particularly to suction producing fans for suction cleaners.

An object of the invention is to provide a new and improved fan for suction cleaners. Another object is to provide a fan formed of steel stampings. A further object is to provide a fan formed of metallic and non-metallic parts. Another object is to provide a fan which can be economically and easily manufactured. Further objects and advantages of the invention will be apparent from the following description and attached drawings, wherein

Figure 1 is a side view of a suction cleaner partly in section showing a fan embodied therein;

Figure 2 is a perspective view of an embodiment of the invention;

Figure 3 is a sectional view of the fan shown in Figure 2;

Figure 4 is a perspective view of another embodiment of the invention, and

Figure 5 is a sectional view of the fan shown in Figure 4.

Referring now to Figure 1, a suction cleaner is shown comprising a main casing 10 which includes a suction nozzle 11, fan chamber 12 and exhaust passageway 13, the latter terminating in a flange 14 to which is removably attached a bag 15. Supported on the main casing 10 is a motor 16 enclosed in a housing 17, the lower wall 18 of which forms the top wall of the fan chamber 12. Disposed in the fan chamber 12 is a fan 19 mounted on the motor armature shaft and rigidly supported on the latter is a pulley 20 which is connected by a belt 21 to an agitator 22 rotatably mounted in the nozzle 11. The cleaner is mounted on wheels 23 and is propelled over the surface being cleaned by a handle 24 pivotally supported on the main casing 10.

Figures 2 and 3 disclose the fan 19 in detail and comprises a shroud 25 of sheet metal stamped to provide an annular flange 26 and a substantially peripheral flat portion 27 which merges into a conical central portion 28 terminating in an annular shoulder 29. The shoulder 29 forms an opening to receive a hub 30 which is secured to the shoulder 29 by means of a washer 31 and by staking the hub 30 at several points 32 over the washer 31.

Fan blades are formed from stamped metal blanks and are constructed integrally in pairs as 33 and 34 which are connected by an integral web 35. The web portion 35 is stamped to conform to the flat periphery 27 and conical portion

28 of the shroud 25 and is rigidly secured to the latter by spot welds indicated at 36.

In use the hub 30 is rigidly attached to the motor armature shaft by the pulley 20, and the 5 marginal flange 26 rotatably seats in the recess 37 provided in the top wall 18 of the fan chamber 12 to form a labyrinth seal for preventing entrance of foreign material therebetween.

Another embodiment of the invention is disclosed in Figures 4 and 5 and comprises a fan 40 having a shroud 41 of plastic material molded to provide a marginal flange 42 and a substantially flat peripheral portion 43 which merges into a conical central section 44 terminating in an integrally formed hub 45.

The fan blades are formed from stamped metal blanks and are constructed in integral pairs as 46 and 47, integrally connected by a web 48 which conforms to the contour of the plastic shroud 41. A recess 49 is provided in the surface of the shroud for each web 48 and the latter seats in the recess 49 whereby the outer surface 50 of the web 48 is flush with the surface of the plastic shroud 41. A plurality of rivets 51 extend through 15 the web 48 and shroud 41 to rigidly secure the fan blades to the shroud.

In use the plastic hub 45 is rigidly secured to the motor armature shaft by the pulley 20 and the plastic marginal flange 42 rotatably seats in the recess 37 in the top wall 18 of the fan chamber 12 to form a labyrinth seal for preventing entrance of foreign material therebetween.

From the foregoing it will be perceived that the metal fan shown in Figures 2 and 3 is formed of stampings and that the web portion of each pair of fan blades is contiguous with the shroud to thereby reinforce the relatively thin metal section of the shroud. In Figures 4 and 5 the web portion of each pair of metal fan blades reinforces the plastic shroud so that the latter can withstand the stresses to which it is subjected.

I claim:

1. A fan comprising a shroud forming the back 45 wall of the fan, a hub at the center of said shroud for attaching the fan to a driving shaft, and fan blades formed in integral pairs connected by web portions, said web portions conforming to the contour of said shroud and resting on the latter, and means for attaching said web portions to said shroud.

2. A fan comprising a shroud forming the back wall of the fan, said shroud having a substantially flat peripheral portion merging into a conical central portion, a hub at the center of said

conical portion for attaching the fan to a driving shaft, and fan blades formed in integral pairs connected by web portions, said web portions conforming to the flat and conical portions of said shroud and resting thereon, and means for attaching said web portions to said shroud.

3. A stamped steel fan comprising a stamped steel shroud forming the back wall of the fan, a hub at the center of said stamped steel shroud for attaching the fan to a driving shaft, and stamped steel fan blades formed in integral pairs connected by web portions, said stamped steel web portions conforming to the contour of said stamped steel shroud and resting on the latter, and means for attaching said web portions to said shroud.

4. A fan comprising a shroud of non-metallic material and forming the back wall of the fan, a hub formed integrally with said non-metallic

shroud for attaching the fan to a driving shaft, and metallic fan blades formed in integral pairs connected by web portions, said metallic web portions conforming to the contour of said non-metallic shroud and resting on the latter, and means for attaching said web portions to said shroud.

5. A fan comprising a shroud of non-metallic material and forming the back wall of the fan, a hub formed integrally with said non-metallic shroud for attaching the fan to a driving shaft, recesses in the surface of said non-metallic shroud, and metallic fan blades formed in integral pairs connected by web portions, said metallic web portions conforming to the contour of said non-metallic shroud and disposed in said recesses, and means for attaching said web portions to said shroud.

ROY D. LIVINGSTON.
